UNITED STATES PATENT OFFICE.

JOSEPH WILLIAM MATTHEWS, OF BRADY, TEXAS.

GATE.

No. 895,386.

Specification of Letters Patent.

Patented Aug. 4, 1908.

Application filed October 19, 1907. Serial No. 328,143.

To all whom it may concern:

Be it known that I, JOSEPH WILLIAM MATTHEWS, a citizen of the United States, and a resident of Brady, in the county of 5 McCalloch and State of Texas, have invented a new and Improved Gate, of which the following is a full, clear, and exact description.

This invention relates to gates, and more particularly to that class of gates known as 10 farm-gates, which can be opened to permit the passage of a vehicle, by a person within the vehicle.

An object of the invention is to provide a simple, strong and efficient farm-gate which 15 can be opened and shut from points remote from the gate itself, which is positive in operation, and which requires the expenditure of little force to close or open it.

A further object of the invention is to provide 20 a device of the class described, which can be operated from a point remote from the gate itself, for instance, by an occupant of a vehicle, and which when opened, remains in that position until a further manipulation of 25 the operating parts closes it.

The invention consists in the construction and combination of parts to be more fully described hereinafter and particularly set forth in the claims.

Reference is to be had to the accompanying 30 drawings forming a part of this specification, in which similar characters of reference indicate corresponding parts in all the views, and in which

Figure 1 is a perspective view of the gate, showing the same in the closed position; Fig. 2 is an enlarged longitudinal section showing a portion of the gate standard, the member movable thereon, and the means for guiding 40 the member upon the standard; Fig. 3 is a plan view of the gate, showing the same closed and indicating in dotted outline the position assumed by the gate when open; and Fig. 4 is an enlarged side elevation showing a portion of the standard and the member movable thereon, partially in section, with portions broken away.

Before proceeding to a more detailed explanation of my invention it should be understood that the gate body used in connection with the device, may be of any common or preferred form.

In the accompanying illustration is shown

a gate fashioned from wood or the like and of the usual three-bar type. If so desired, the 55 gate body may be fashioned from metal and wire netting or from any other suitable material.

While my invention is particularly useful in connection with farm-gates it is equally 60 applicable to similar devices for other purposes, for instance, in connection with railway grade crossings, warehouse doors and the like.

The arrangement of the gate is such that it 65 can be operated by an occupant of a vehicle it is desired to drive through the gate and for which purpose the gate must be opened; at the same time, it is necessary further to manipulate the gate to close the same after 70 the vehicle has passed therethrough. While this necessitates two operations, it is of advantage in that the gate does not prematurely close and interfere with the passage of the vehicle as is often the case when the gate 75 is arranged to close automatically.

Referring more particularly to the parts, 1 represents the body of the gate, consisting in the form of the device illustrated in the drawings, of the cross-bars 2 joined by the 80 end uprights 3 and the middle upright 4; the uprights comprise similar strips or slats arranged at the opposite faces of the bars 2 and are secured in position in any suitable manner. The gate body is arranged at an opening of a wall or fence 5, which is provided with gate posts 6, for the purpose. Substantially in the center of the gate opening is arranged an upright standard 7, upon which the gate body is arranged to swing by means 85 of bolt brackets 8. If so desired, the gate may be provided with latches 9, adapted to engage catches 10, mounted upon the gate posts and serving to lock the gate in position.

Near the upper end the standard 7, which 95 is preferably round in cross-section, has formed thereon pairs of opposite, substantially vertical grooves or guideways 12. The grooves 12 of each bar lie adjacent and parallel though separated by a web 11. The 100 grooves 12 have the opposite ends connected by spirally disposed grooves or guides 13 which intersect at substantially central points. A sleeve 14 is slidably arranged upon the standard 7 and has eyes 15 carrying 105 the upper ends of hangers 16. The lower

ends of the latter are secured to eye brackets 17, bolted or otherwise suitably secured to the top bar 2 of the gate body. The sleeve 14 has further eyes 18, to which are joined the lower ends of links 19. The upper ends of the latter are secured to a yoke bar 20, carrying a U-bracket 21 by means of an eye bolt 22. The sleeve 14 has dogs 23 pivotally mounted therewithin by means of rivets 24.

10 Each of the guides co-acts with a dog 23 as will appear more clearly hereinafter.

At opposite sides of the gate are arranged posts or uprights 25 carrying at the upper ends pivoted levers 26. The adjacent ends 15 of the levers 26 are pivoted by means of a pin 27 to the U-bracket 21. The opposite or remote extremities of the levers are provided with depending cords or chains 28, having handles 29 by means of which they can be 20 conveniently manually controlled. The uprights 25 have catches 30, adapted to co-act with the latches 9 to hold the gate open.

The weight of the gate body is carried by the sleeve 14 through the hangers 16; consequently, the normal position of the sleeve is such that the dogs 23 are arranged at the lower ends of the substantially vertical guideways 12, as is shown most clearly in Figs. 2 and 4. When it is desired to open 30 the gate, a downward pull on one of the depending cords 28 operates a lever 26 and moves the sleeve 14 upwards. When this occurs, the dogs travel vertically in the respective guideways 12 until the upper limit 35 of the latter is reached. On releasing the operating member the weight of the gate pulls the sleeve downward. The dogs however, instead of moving backward along the guideways 12, enter the spiral guideways 13 40 and advance to the bottom of the opposite guideways 12 as the guideways 12 near the upper ends are formed to incline the dogs slightly, to direct them into the spiral guideways 13. In doing this the sleeve is rotated so that the gate is swung into a position 45 substantially at right angles with its original position and rests against the uprights 25, leaving the gate-way open. When it is desired to close the gate, the sleeve is again raised by means of one or the other of the levers, and on releasing the sleeve the latter is rotated by the passage along the opposite guideways 13 of the dogs 23, thereby 50 returning the gate to its original or closed position. To insure that the dogs travel along the substantially vertical guideways 12 when the sleeve is raised, the lower portions of the guideways 13 are cut away, as is shown most clearly in Figs. 2, 3 and 4.

60 It will be understood that in opening or closing the gate, the initial movement of raising the gate body releases the same from the catches upon the gate posts or uprights; consequently, the gate when closed or held

open is always firmly mounted in position 65 and it can be easily unlatched by a special manipulation of the operating parts.

Having thus described my invention, I claim as new and desire to secure by Letters Patent:—

1. A gate, comprising a gate body, a standard, a member movable longitudinally of said standard and controlling said gate body, and means for manually operating said member, said standard having a guideway for directing said member, said guideway comprising opposite guide grooves arranged longitudinally of said standard, and curved guide grooves connecting the said guide grooves.

2. A gate, comprising a gate body, a standard, a sleeve upon said standard and movable longitudinally thereof, said sleeve controlling said gate body, and means for manually operating said member, said standard having opposite guideways for directing said member, each of said guideways comprising opposite guide grooves substantially parallel to the longitudinal axis of said standard, and spirally disposed guide grooves connecting the opposite ends of said first guide grooves and intersecting therebetween, said sleeves having pivoted dogs adapted to travel in said guideways, said guide grooves substantially parallel to the longitudinal axis of said standard being formed near the upper ends to incline said dogs to direct the same into said spirally disposed guide grooves.

3. A gate, comprising a gate body, a standard, a sleeve movable longitudinally of said standard and controlling said gate body, and means for manually operating said member, said standard having a guideway for directing said sleeve, said sleeve having a part adapted to engage said guideway, said guideway comprising opposite guide grooves arranged longitudinally of said standard, and curved guide grooves connecting said first guide grooves near the opposite ends.

4. A gate, comprising a gate body, a standard having a pivotal connection with said body and provided with a guideway, a member slidably arranged upon said standard and operatively engaging said guideway, said member controlling said gate body, and manually operable levers controlling said member, said guideway comprising opposite guide grooves arranged longitudinally of said standard, and curved guide grooves connecting the opposite ends of said first guide grooves.

5. A gate, comprising a gate body, a substantially central standard pivotally carrying said body, said body being movable longitudinally of said standard, said standard having guideways, a sleeve slidably mounted upon said standard and having pivoted dogs engaging said guideways, manually operable levers controlling said sleeve, and hangers

connecting said sleeve and said gate body, said guideways each comprising opposite guide grooves substantially parallel to the longitudinal axis of said standard, and spirally disposed guide grooves connecting the opposite ends of said first guide grooves.

In testimony whereof I have signed my

name to this specification in the presence of two subscribing witnesses.

JOSEPH WILLIAM MATTHEWS.
